United States Patent Office

Des. 193,288
Patented July 24, 1962

193,288

BOAT

Milton M. Siegel, Los Angeles, Calif., assignor to Columbia Plastics Corp., Culver City, Calif., a corporation of California

Filed Oct. 28, 1960, Ser. No. 62,801

Term of patent 14 years

(Cl. D71—1)

Fig. 1

Fig. 2

Fig. 3

Fig. 4

Fig. 5

FIGURE 1 is a front perspective view of a boat showing my new design;
FIGURE 2 is a rear perspective view;
FIGURE 3 is a bottom plan view;
FIGURE 4 is a section taken at line 4—4 of FIGURE 3; and
FIGURE 5 is a front elevational view.

I claim:
The ornamental design for a boat, substantially as shown.
